UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-CHANGING MECHANISM.

Application filed October 31, 1922. Serial No. 598,110.

This invention relates to a shuttle changing loom of the general type disclosed in the prior patent of E. H. Ryon, No. 1,476,847, issued December 11, 1923.

5 It is one object of my invention to improve the construction therein shown by providing improved shuttle feeding mechanism and particularly by providing a construction in which all parts of the shuttle feeding mechanism remain normally at rest, the mechanism becoming operative only at the time of shuttle transfer.

10 Another object is to provide an improved binder construction by which a single binder is used for both shuttle boxes at the replenishing end of the loom.

15 My invention further relates to arrangements and combinations of parts which will be hereinafter described and more particularly pointed out in the appended claims.

20 A preferred form of the invention is shown in the drawings, in which

Fig. 1 is a partial side elevation of a shuttle changing loom embodying my improvements, the parts being in normal running condition;

25 Fig. 2 is a vertical section, taken on the line 2—2 in Fig. 1;

Fig. 3 is a plan view of the shuttle box and binder;

30 Fig. 4 is a sectional elevation taken along the line 4—4 in Fig. 2;

Fig. 5 and 6 are views similar to Fig. 4 but showing the parts in successive different positions;

35 Fig. 7 is a longitudinal sectional elevation of the clutch connection from the cam shaft, taken on the line 7—7 in Fig. 1;

Fig. 8 is a side elevation of the clutch disc, taken along the line 8—8 of Fig. 7;

40 Figs. 9 and 10 are side elevations similar to Fig. 1 but showing the parts in successive different positions, and

Fig. 11 is a detail rear elevation looking 45 in the direction of the arrow 11 in Fig. 9.

Referring to the drawings, I have shown a loom frame 20 in which a lay is mounted on the usual swords 21 pivoted on a rock shaft 22 (Fig. 2) in the lower portion of the frame 20. A regular shuttle box 23 and an auxiliary shuttle box 24 are slidably mounted in a lay end 25 and are supported on a lifter rod 26. The rod is connected by a give-way link 27 to the end of

a lifter lever 28 mounted on a fixed stud or pivot 29 on the frame 20.

An actuating lever 30 is also pivoted on the stud 29 and has a rearwardly extending arm 31 supporting a cam roll 32. The roll 32 is engaged by a cam 33 on the usual bottom or cam shaft 24 and the lever 30 is thus regularly oscillated as the shaft 24 revolves.

5 A latch 35 is pivoted on the lever 30 and has an offset end 36 adapted to be projected through an opening in the lever 30 into position to engage the under side of the lifter lever 28. The position of the latch 35 is determined by weft detecting mechanism, not shown. When the supply of weft in a 70 running shuttle is substantially exhausted, the latch is moved under the lever 28 and the lifter rod 26 and shuttle boxes 23 and 24 are thus raised to eject the exhausted shuttle.

75 A shuttle magazine 37 (Fig. 1) is mounted in fixed position on the loom frame 20 and a shuttle holder 38 is slidably mounted beneath the magazine 37. This holder 38 is normally positioned as indicated in Fig. 80 1, so that a spare shuttle S' enters the auxiliary shuttle box 24 at each forward movement of the lay.

When a shuttle transfer is indicated, the boxes start to rise, as indicated in Figs. 9 85 and 5 and the shuttle S' is removed in the box 24 from the holder 28. The rising movement is continued during the backward movement of the lay and the final raised position of the boxes is shown in Fig. 10 at 90 which point the exhausted shuttle S is ejected from the regular shuttle box 23 and the new shuttle S' is picked from the auxiliary box 24.

95 The parts thus far described are substantially as shown in the prior application of Ryon above noted and form no part of my present invention.

An important part of my invention, however, relates to the provision of a binder 40 pivoted at 41 (Fig. 3) on a bracket 42 fixed to the lay end 25. A spring 43 is also mounted in fixed position and yieldingly presses the binder against the front side of the shuttle. A guide or stop 44 is fixed to the rear part of the lay end, as indicated in Fig. 5 and is arched upward to permit vertical movement of the shuttle boxes. The

arm 44 engages the front side of the binder and limits forward displacement thereof.

The end of the binder is also engaged by the usual protector finger 45 by which the loom may be stopped if a shuttle fails to box. The lower edge of the binder 40 is preferably inclined or beveled as shown in Fig. 5 so that the binder may be readily pressed forward as the new shuttle S' is 10 raised to running position.

Several important advantages are attained by the use of a single binder mounted in fixed vertical position and cooperating with the running shuttle whether in the regular shuttle box 23 or in the auxiliary shuttle box 24. As only a single binder is used, the pressure of the binder is uniform and the shuttle is boxed in the same position, whether in the auxiliary or the regular shuttle box. Furthermore, reference to the Ryon application will show that the use of a single fixed binder enables me to omit many movable parts therein shown and to substantially simplify the transfer mechanism.

25 The shuttle carrier or slide 38 (Fig. 1) is connected to the upper end of a lever 50 mounted on a fixed pivot 51 and connected by a link 52 and give-way connection 53 to a cam lever 54 pivoted at 55 to a bracket secured to the frame 20. A cam roll 56 on the lever 54 is engaged by a cam 57 rotatable on a stud or shaft 58. The cam 57 is loose or the shaft 58 but is fixed to a large gear 59 engaged by a pinion 60 (Fig. 7) loose on the cam shaft 34.

40 The hub of the cam 33 (Fig. 7) on the shaft 34 is provided with a clutch disc 61 (Fig. 8) having a notch or recess 62 adapted to receive a stud 63 (Fig. 7) in the adjacent face of the pinion 60. The pinion 60 has a grooved hub 64 which receives the forked end of a lever 65 pivoted at 66 on a bracket secured to the loom frame. A light 45 spring 67 (Fig. 2) normally holds the pinion 63 in outward position against the end of a heavier coil spring 68 loose on the cam shaft 34. A grooved collar 69 is slidable on the end of the shaft 34 and is engaged by the forked upper end of a bell crank 70 (Fig. 11) mounted on a fixed pivot 71 and having its lower offset end 72 projected into the path of a rearwardly extending arm 73 (Figs. 1 and 2) fixed to the lifter lever 28.

55 When the lifter lever 28 is raised upon indication of shuttle transfer, the arm 73 is depressed and the bell crank 70 is thus moved to compress the coil spring 68 and force the pin 63 against the side of the continuously moving clutch disc 61. When the 60 pin 63 is aligned with the notch or recess 62, the pin is forced into the notch and the pinion 60 then revolves with the cam 33 and thus actuates the gear 59 and cam 57. In this position the shuttle holder 38 receives a 65 spare shuttle S' from the magazine 37 and

is thereafter moved rearward to the normal position shown in Fig. 1.

A spring 75 acts through the lever 54 and link 52 to move the shuttle holder 38 forward to shuttle receiving position, the parts 70 being thereafter moved rearwardly to normal position by the cam 57, acting through the give-way connection 53.

A second cam 76 is rotatable with the cam 57 and gear 59, this cam serving to raise a 75 link 77 connected to actuate mechanism (not shown) for transferring the exhausted shuttles in a shuttle storage receptacle. A cam roll 78 on the link 77 enters a depression 76a in the cam 76 when the link is in 80 its lowest position and acts to yieldingly hold the gear 59 and parts associated therewith in normal inoperative position when the pinion 60 is released from the driving disc 61.

This release is accomplished by a cam lug 79 on the side of the gear 59 which engages an upwardly extending projection 80 on the forked lever 65. The cam lug 79 engages the projection shown in Fig. 1, the momentum of the parts and the depression 90 in the cam 76 causing the gear 59 to advance slightly beyond the position in which it engages the projection 80. The driving and control mechanism for the gear 59 is not claimed herein as it forms a part of the 95 subject matter of the co-pending application of A. J. Chevrette, Serial No. 598,123, filed Oct. 31, 1922.

It will be noted that the gear 59 and cams 57 and 76 remain at rest after their return to normal position and have no further movement until after an indication of further weft exhaustion. This construction has important advantages over the construction heretofore used in which parts of the 105 actuating mechanism for the shuttle holder 38 were continuously moved by a cam on the cam shaft 34.

Having thus described my invention and the advantages thereof, I do not wish to be 110 limited to the details herein disclosed otherwise than as set forth in the claims, but what I claim is:—

1. In a shuttle changing loom, a lay, driving mechanism therefor, a pair of shuttle boxes vertically movable thereon, a shuttle magazine, a shuttle holder normally maintained in rearward transfer position, a lever connected to said shuttle holder, and actuating means including a member effective on 115 rotation thereof to move said lever and reciprocate said holder to remove said shuttle from said magazine and to present said shuttle in transfer position, said rotatable member of said actuating means being normally disconnected from the loom driving mechanism and being normally at rest, but being operatively connected to said driving mechanism immediately after each shuttle 120 transfer. 130

2. In a shuttle changing loom, a lay, a pair of shuttle boxes vertically movable thereon, a shuttle magazine, a shuttle holder normally maintained in rearward transfer position, and actuating means to reciprocate said holder to remove a shuttle from said magazine and to present said shuttle in transfer position, said means including a cam normally at rest, driving mechanism therefor rendered operative only upon indication of transfer, a cam lever, and a give-way connection between said lever and said shuttle holder.
- 5 15
3. In a shuttle changing loom, a lay, a pair of shuttle boxes vertically movable thereon, a shuttle magazine, a shuttle holder normally maintained in rearward transfer position, and actuating means to reciprocate said holder to remove a shuttle from said magazine and to present said shuttle in transfer position, said means including a cam normally at rest, driving mechanism therefor rendered operative only upon indication of transfer, a cam lever, and a give-way connection between said lever and said shuttle holder.
